CLAIM

The ornamental design for a golf grip, as shown and described.

DESCRIPTION

FIG. 1 is a perspective view of a golf grip, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of a portion of FIG. 1; and,

FIG. 10 is an enlarged view of a portion of FIG. 2.

The broken line showing of the golf grip is for the purpose of illustrating article and forms no part of the claimed design.
